AERIAL CABLE SUPPORT, OR SIMILAR ARTICLE

James P. Markham, Webster St.,
Milford, N.H. 03055

Filed Apr. 21, 1969, Ser. No. 16,827

Term of patent 14 years

Int. Cl. D2—03

U.S. Cl. D8—230

FIG. 1 is a front elevation view of my aerial cable support, or similar article.

FIG. 2 is a top plan view of FIGURE 1; and

FIG. 3 is a bottom plan view of FIGURE 1.

The reverse side is identical to that shown in FIGURE 1.

The broken line view of a typical supporting clamp and bolt member is not intended to form a part of the disclosed design, but is included only to show environmental utility of my cable support.

I claim:

The ornamental design for an aerial cable support, or similar article, substantially as shown and described.
